UNITED STATES PATENT OFFICE.

PHILIP S. REYMAN, OF MOUNT CARMEL, ILLINOIS.

STAVE-JOINTING MACHINE.

1,158,004.

Specification of Letters Patent.

Patented Oct. 26, 1915.

Application filed January 12, 1912. Serial No. 670,800.

To all whom it may concern:

Be it known that I, PHILIP S. REYMAN, a citizen of the United States, residing at Mount Carmel, in the county of Wabash and State of Illinois, have invented new and useful Improvements in Stave-Jointing Machines, of which the following is a specification.

This invention relates to machines for jointing barrel staves and other conical and tapered blanks, for various purposes. Its object is to provide an improved construction and arrangement of mechanism which will enable stave and other blanks of any width to be fed continuously to an endless carrier which passes them between a pair of saws or other disk cutters adapted to operate upon the edges of the blanks and trim them to the proper bevel and longitudinal curvature, so that when staves thus treated are assembled into a barrel their edges will all coincide with planes radiating from the center of said barrel.

In the following description I shall assume that the machine is used for the jointing of barrel staves, but it will be understood that when a stave or stave blank is mentioned I do not intend thereby to limit the machine to such uses.

In a prior Patent No. 974,518, I have disclosed a machine for jointing staves in which each stave is placed upon a carriage which can be moved back and forth between a pair of saws; said carriage having a curved surface on which the stave is rocked during its passage between the saws in order to cause the saws to operate at points separated more and more as they approach the middle of the stave and then at points which gradually approach as they proceed toward the end of the stave. In my present invention the stave lies flat upon an endless carrier belt which is raised and lowered as the stave passes between the saws, in order to give the proper curvature to the edges and insure the desired bilge to the completed barrel. In my patent aforesaid the saws can be adjusted angularly at different distances apart to accommodate staves of different widths. In my present invention the saws can be adjusted not only in that manner but also vertically on their supports to compensate for wear. During the passage of the stave between them, they are automatically turned or swiveled on vertical axes, so that they

conform closely to the longitudinal curve of the edges of the stave and maintain their teeth always at the proper angle to said edges.

The endless carrier is preferably a chain, and in order to permit it to be raised and lowered during the passage of each stave between the saws, I have provided an eccentric sprocket wheel at one point in its travel which automatically slacks the chain and takes it up again at the proper times.

The invention will be better understood from the following detailed description, read in connection with the accompanying drawings, in which—

Figure 1 is a side elevation, partly in section of a stave-jointing machine embodying my improvements. Fig. 2 is a plan view taken on the line 2—2, Fig. 1, and on a larger scale. Fig. 3 is a cross sectional elevation taken on the line 3—3, Fig. 1 on a larger scale. Fig. 4 is a cross sectional elevation, taken on the line 4—4, Fig. 1, on a larger scale. Fig. 5 is a cross section taken on the line 5—5, Fig. 1, through the driving shaft and the cams which cause the saws to conform to the longitudinal curve of the stave. Fig. 6 shows one of the movable leaves with the shoe hinged thereto. Fig. 6^a is a plan view of the same. Fig. 7 is a plan view of the driving shaft, showing a section of the main spur gear and eccentric sprocket. Fig. 8 is a plan view of the stave supporting shoes and one of the saws. Fig. 9 is a sectional plan view on the line 9—9, Fig. 5. Figs. 10 and 11 are diagrams illustrating the relative widths and curvatures of the staves. Fig. 12 is a perspective view, somewhat enlarged, showing one of the saws and its holder. Fig. 13 is a sectional plan view of the chain sprocket at the left hand end of Fig. 1. Fig. 14 is a similar view of the sprocket at the right-hand end of Fig. 1. Fig. 15 is a cross section of the left-hand end of the chain support, taken on line 15, Fig. 1. Fig. 16 is a similar cross section at line 16—16, Fig. 1. Figs. 17, 18 and 19 show the manner in which the saws conform to the longitudinal curve of the stave. Fig. 20 is a cross section of the main shaft, showing the levers and links which operate the devices for converging the saws. Fig. 21 is an upright cross section of the machine on the line 21—21, Fig. 1. Fig. 22 is a cross section at line 22—22, Fig. 1. Fig. 23 is a

detail section on the line 3—3, Fig. 1. Fig. 24 is a section on the line 24—24, Fig. 1. Fig. 25 is a side elevation of one of the guide bars for the chain carrier. Fig. 26 is a side elevation of the central support for the chain carrier. Fig. 27 is a side elevation of one of the movable leaves for supporting the stave blank. Fig. 28 is a top plan view of the entire machine, the saws being abnormally spaced apart, the leaves being broken away and the shoes and presser rolls omitted.

At the outset, it may be well to call attention to the shape of a stave. A barrel is not generally a true spindle in shape, that is to say the bilge or curvature does not run from end to end. The end portions of a barrel are conical, the bilge occupying the middle portion of the barrel. When considering a flat stave, therefore, the edges at the ends, while tapering toward each other, are straight for several inches. Between these straight portions the edges have a longitudinal curve, the two curves being most widely separated at the middle of the stave where they are tangent to lines parallel with the center line of the stave. The stave when produced is a true geometric section of the completed barrel. The wider the stave, the greater the bilge or difference in width between the ends and its middle point. For instance, a stave two inches wide at the ends will be approximately two and three eighths inches wide at the middle, while a stave six inches wide at the ends will be seven and one eighth inches wide at the middle. I accomplish the jointing of such a stave by means of two revolving saws whose planes are radial to a common horizontal axis about which they can be adjusted. The stave passes between them in a horizontal position, being lifted to increase the width and lowered to narrow it. Now in order to form the straight portions or "quarters," as they are termed, it is necessary for the saws to be closed or converged toward each other at their rear edges before starting the stave in between them. In other words, they must be partially swiveled or rotated upon vertical axes substantially coinciding with the points at which the cutting is effected. The stave enters, and as it is gradually lifted the saws act at more widely separated portions and form the "quarter." Upon reaching the bilge, the saws must be gradually swiveled, the angles between their horizontal diameters becoming greater until the widest point of the stave is reached, at which position the two saws have their horizontal diameters parallel, and the stave is at its highest level. As the saws follow the curvature of the stave toward its other end, the stave meanwhile descending, their horizontal diameters gradually converge in the other direction until they stand at the proper angle to com-

plete the other "quarter" of the stave, while said stave drops to its original level. Now on a stave six inches wide at the ends, the increase in width at the middle is one and one eighth inches, while on a stave two inches wide at the ends the increase at the middle is only three eighths of an inch. As the staves are of uniform length this means that the divergence of the saws when cutting the quarters must be greater for the wide stave than for the narrow one.

The machine which I am about to describe is an organized instrumentality for causing the stave to gradually rise and fall during its forward travel between the saws, and also for causing the revolving saws to converge, become parallel and then converge oppositely as the stave passes between them, and to automatically adjust their divergence at the quarters to correspond with the width of the stave which is under treatment.

The working parts are mounted upon frame 1 of suitable height, in the lower part of which is located the main shaft 2, journaled in bearings 3, and carrying a suitable pulley or other means whereby power can be transmitted to it. In the drawing (Fig. 5), I have shown a friction disk 4 secured to said shaft by a key 5 and arranged adjacent to a loose belt pulley 6. Bearing 7 against the hub of this pulley is a loose sleeve 7 whose opposite end is provided with spiral cams 8 co-operating with stationary spiral cams 9 on the end of the bearing. By partially revolving this sleeve, the spiral cams cause it to slide lengthwise on the shaft 2 and thereby press the pulley into frictional contact with the disk 4 and impart rotation to the shaft.

A pinion 10 on the inner end of the shaft 2 meshes with a spur gear 11 on a driving shaft 12 journaled in bearings 13. A driving sprocket 14 is fastened to said gear in any suitable manner, said sprocket being eccentric to the shaft 12 for a reason which will appear later. An endless belt passes around the sprocket 14 and two supporting sprockets 15 16 arranged at the ends of the machine and on a higher level than the driving sprocket. The belt is kept taut at all times by a belt tightener sprocket or roller 17 which is journaled in one end of a pair of levers 18, pivoted at their other end to the frame 1 and urged against the belt by a spring 19 which abuts at one end against said lever and at its other end against a boss on the frame 1. The endless belt is preferably a chain 20, as shown at the right hand end of Fig. 1. At suitable distances, corresponding with the length of a stave x , special links are provided with means for engaging said stave, so that it will be carried by the chain in the direction of the arrow y , Fig. 1. One of these links has a wedge-shaped notch 21 into which the

forward end of the stave is thrust and by which it is clamped down upon the chain. The rear of the stave is engaged by a shoulder 22 on another link, which acts to force the stave firmly into the hooked link and also to push the stave along as the chain travels between the saws. Several sets of these special links are provided, their number depending upon the size of the machine 10 and length of the staves to be operated upon. By using higher hooks and shoulders, two or more staves can be jointed at one time.

Sprocket 14 makes one revolution in 15 jointing a stave, the pitch circumference of said sprocket being equal to the distance between a pair of links 21, 22, plus the short distance on the chain for carrying the stave out from between the cutters, and in the machine 20 illustrated the total length of the chain is four times this circumference.

The supporting or idle sprockets 15, 16 are not mounted upon the frame 1, but are secured to a narrow rigid chain guide over 25 which the chain travels and which is capable of being raised and lowered as the stave passes between the saws. This chain guide, at the left hand of Fig. 1 consists of a flat plate 23 lying in a horizontal position and fastened by screws 24 to the top of a block 25. Resting on this plate are two parallel angle irons 26 spaced apart a suitable distance for the chain to slide freely between them, the upright flanges of said angle irons 30 serving as guides for said chain. The screws 24 pass through the horizontal flanges of said irons and secure them to the plate 23. The block 25 is made in halves which are riveted to the opposite sides of a thin bar 27 which extends from the block to the right hand end of the machine. Beginning at the right hand end of the block the upper edge of said bar is on the same level as the top of the plate 23, while its thickness is the same as that of the chain, which 45 rests upon it. Upright guide plates 28 are secured on opposite sides of the bar 27 throughout the greater part of the right hand end of the machine, to guide the chain in a straight line in its travel along said bar.

A U-shaped casting is slipped upon the right hand end of the bar 27 from below said casting being adjustable lengthwise of 50 said bar by means of the slots 29 through which the securing bolts 30 pass. The right hand end of this casting is bifurcated to form arms 31 between which the right hand idle sprocket 16 is journaled on an arbor 32. The casting can be moved lengthwise by 55 means of an adjusting screw 33 abutting against a lug 34 on said casting and meshing with a screw-threaded hole in a boss 35 on the under side of the bar 27. This boss 60 and the block 25 form the points of sup-

port for the chain guide and its guides. A pair of links 36 webbed together are pivoted to opposite sides of the boss 35 and also to lugs 37 on the frame 1. A similar pair of links 38, of the same length as the links 36, 70 and preferably connected by a cross bar 38' are pivoted to lugs 39 mounted on the frame and also to an arbor 40 extending transversely through the cheek pieces 41 which are bolted to the sides of or integral with the block 25. These two pairs of links are parallel, so that the chain guide can be raised and lowered and yet always preserve a horizontal position; the action being like 75 that of the well-known parallel ruler.

The mechanism for raising and lowering the chain guide comprises a roller 42 carried by two rocker arms 43 pivoted at 44 to the frame of the machine. One of these rocker arms has an extension 45 to which is 80 pivoted one end of a connecting rod 46 whose other end is connected to a crank pin 47 on the main spur gear 11. The roller 42 bears against a cam 48 secured to the bar 27. This cam is preferably pivoted to said bar 85 at 49 and its lower end is adjustable by means of a set screw 50 which passes horizontally through a thickened depending portion 27' of the bar 27. This adjustment is for the purpose of varying the bilge given 90 to the stave. The portion 27' of the bar is held between guide-plates 51 secured to chairs 52 which are bolted to the frame 1, for the purpose of guiding bar 27 truly vertical. A set screw 53 is tapped into the under side of the portion 27' and abuts against the frame between said chairs, so that the bar 27 can be adjusted vertically at this point, and at the same time receive a solid support from said frame when in its lowered position. It will be understood that 100 at each revolution of the driving shaft the connecting rod actuates the rocker arms, and the roller acts upon the cam 48 and lifts the chain guide, the portion 27' sliding vertically between the guide plates 51. As the roller recedes and the chain guides drop, the weight of the guiding bars and the chain, and also the pull of said chain upon the back sprocket 15 all act to keep the cam 48 105 in close contact with the roller. The configuration of the cam 48, taken in connection with the varying rate of speed and travel of the roller 42 in its continuous oscillation to and fro, can be made to give the 110 chain guide and the shoes hereinafter mentioned the proper rising and falling movements and the dwell to produce the desired shape of stave. The necessary dwell while the stave is passing between the saws is produced by the rocker arm 43 and roller 42 115 swinging out to the right and back, from the upper end of the cam 48.

Extending from the front of the machine, that is to say, the right hand end in Fig. 130

1, and located on either side of the guide plates are two movable leaves 54 which are indicated by dotted lines in Fig. 1, and shown more clearly in Figs. 6 and 6^a, and 5 form part of the table on which the stave blank is temporarily supported. These leaves are bowed outwardly and are movable laterally in order that they may be kept underneath the outer edges of the stave, that is 10 to say, just within the kerfs cut by the saws, to support said stave and determine the width of stave a given blank will make. In order to understand the way in which these leaves are mounted and operated, it will be 15 necessary now to explain the mounting of the saws.

Each saw 55 is secured by screws 56 to a collar 57 which is screwed upon a screw-threaded central stud 58 projecting from a 20 hub 59 on a mandrel 60. Inner and outer bearings 61 for said mandrel are provided in a forked standard 62 and between said bearings a belt pulley 63 is secured to said mandrel. The standard is fastened by screws 64 25 to a bracket. Inasmuch as these brackets are dissimilar in shape, the right hand one in Figs. 4 and 12 is numbered 65 and the left hand one 66. Each bracket is mounted on a joint, so constructed that it is capable of 30 movement about two axes at right angles to each other. The preferred mode of mounting is illustrated in the drawings, and comprises a horizontal shaft 67 running lengthwise of the machine and free to rotate in 35 bearings 68 supported by the frame 1. Fitting between said bearings are two blocks 69 70 each having a circular groove fitting the exterior of the shaft, the block 69 being below and the block 70 being above said 40 shaft. For a portion of their length the blocks are interiorly recessed to receive a short sleeve 71 which has a slot in its under side. A stud 72 is screwed radially into the shaft through said slot, and another radial 45 stud 73 is screwed into the upper side of said sleeve, each stud passing snugly through a hole in its corresponding block 69, 70. The bracket has at its lower end a circular enlargement 65' provided with an annular shoulder 65'' fitting a rabbet 69' on the block 69. The block and the enlargement have flat meeting faces, and in each face is an annular groove concentric with the stud 72 to contain a plurality of antifriction 50 balls 74. The stud 72 passes centrally through the enlargement 65', so that the bracket 65 is thus pivoted to the shaft 67 but on an axis radial thereto. The upper bracket 66 is similarly pivoted on the radial stud 60 73, by means of a circular enlargement 66', which has a shoulder 66'' fitting the rabbet 70' on the block 70, and a ball bearing 75. But since the upper stud 73 is screwed into the sleeve 71 instead of into the rotatable 65 shaft 67, the two brackets can be independ-

ently rotated or tilted about the axis of the shaft, in addition to the independent rotation of each about its stud.

The weight of each bracket and its saw is yieldingly supported by a helical spring 76 interposed between a shoulder on the under side of the bracket and some portion of the frame 1, as clearly indicated in Fig. 4. For rotating the brackets about the axis of the shaft 67 in order to tilt the saws 55 and thus vary the angle between them with respect to the varying widths of the staves, each bracket is pivoted to a rod 77 whose lower end has a horizontal eye 78 received upon a pintle 79 projecting centrally upward from a vertical plunger 80 whose vertical axis intersects the center of the shaft 67 at the point from which the pivots 72 73 radiate. On one side of said plunger is a rack 81 meshing with a pinion 82 secured upon shaft 83 which is suitably journaled in the frame and has a lever 84 for operating it. The lever has a latch 85 co-operating with a notched quadrant 86, so that it can be locked at any desired position. A thrust roller 87 bears against the back of the plunger to keep it in mesh with the pinion. The roller and pinion are inclosed in a box 88 with a dust-excluding cover 89.

The saws are arranged with their planes of revolution radial to the axis of the shaft 67, so that when the lever 84 is operated and the brackets 65 66 are swung up or down as the case may be by means of the supporting rods 77, the saws always preserve this radial relation to the shaft 67; the result of the movement of the brackets being simply to tilt the saws simultaneously and increase or diminish the angular distance between them.

Each saw mandrel 60 lies in a plane transverse to the shaft 67 and the line of travel of the stave blank. In my prior patent mentioned heretofore the planes of the two mandrels coincided at all times and were perpendicular to the axis of the shaft about which they could rotate. But in my present machine, I have provided means for shifting the planes of the saw mandrels so that they will at all times stand at an angle on one side or the other of a plane exactly perpendicular to that of the shaft 67; the object being to enable the saws to follow more closely the longitudinal curvature of the edges of the stave, as explained at the beginning of this description.

It will be noticed that the axis of the stud 72 is in line with the cutting point of the saw carried by bracket 65, and that the axis of stud 73 is similarly in line with the cutting point of the saw carried by bracket 66 and that these axes are in the same vertical plane as the axis of the pintle 79 upon which the rods 77 are free to swivel with the brackets 65 66. Any swiveling of the brackets about these studs will therefore result in turning

the saws on vertical axes, and will cause their rear edges to approach or separate, as the case may be, their front edges remaining substantially stationary. This converging and diverging action of the saws at the rear occurs during the passage of each stave, and is therefore effected by mechanism which operates in time with the other parts of the machine.

- 10 Extending rearwardly from each bracket 65 66 is a tail piece 90, having at its rear end a transverse portion 91 which rests upon a supporting roller 92 journaled upon a stud 93 which is carried by the block or lug 39.
- 15 To maintain these parts in proper relation, the rollers may be grooved and the underside of the portions 91 shaped to engage with said grooves. Depending from each tail piece is a cam finger 94 having flat parallel sides. The two fingers are arranged side by side with just sufficient space between them when the saws and the brackets are parallel with each other to receive two parallel studs 95 provided with antifriction rollers 96 which are in contact with the inner faces of the fingers. The studs are carried by a forked arm 97 pivoted to the lugs 98 projecting from the block 39. A strap 99 is secured to said arm and extends around 20 in front of the fingers and rollers, the outer ends of the studs being secured to said strap. The side portions of the strap engage with the outer faces of the fingers for the purpose of holding fingers or cams 94 snugly against rollers 96 at all times. An arm 100 projects downwardly from the arm 97 and is pivoted to two links 101 and 102 connected respectively to two levers 103 104 which are fulcrumed in blocks 105 supported by 25 the frame of the machine, and adjustable by means of set screws 106, for adjusting the time of action of the rollers 96; also the dwell when forming straight quarters on stave joints. These two blocks are located on opposite sides of the eccentric sprocket 14, on one side of which is an eccentric surface 107 engaging with rollers 108 108' pivoted on the levers 103 104, so that as the sprocket revolves this eccentric or cam will actuate 30 the levers and rock the bell crank lever composed of the arms 100—97 and thus raise and lower the rollers 96. Owing to the fact that the faces of each finger 94 are substantially parallel with the plane of the saws carried by its bracket, (see Fig. 5) the axis of inclination of brackets 65—66, shown in Fig. 5, is the axis shaft 67, as dotted in at intersection of curved dotted line 9—9, said shaft being the axis of brackets carrying cam fingers, bell crank lever arm 97, carrying rollers 96—96, are shown at their central elevation, therefore brackets are in a parallel position horizontally—therefore when saws attached to brackets are spaced a distance apart, the cam fingers necessarily 35 assume a similar angle, hence any movement of arm 97 downwardly would cause brackets to diverge while an upward movement would cause brackets and saws to converge a proportionate amount depending on angular separation of saws as shown by dotted lines 94^a. It follows that when the saws are tilted apart said fingers stand at a variable angle to the perpendicular line of movement of the rollers, which causes said rollers to push said fingers apart when they descend. During the upward movement of said rollers, the said portions of the strap 99 act to force the fingers toward each other a variable amount. It follows, therefore, that at each revolution of the cam 107 the brackets 65 66 will be swiveled on their studs 72 73; first in one direction and then in the other, so that the saws will be first converged at the rear and then separated a proportionate amount conforming to width of stave being operated upon, which is effected by the changed angularity of the cam fingers 94, occurring simultaneously with the changed angularity of the plane of the saws in spacing the same for varying widths of staves.
- 40 Returning now to the leaves 54, it will be observed that at their front, or right hand ends in Fig. 1, they are provided with downwardly extending arms 54' which are pivoted to levers 109, one of which is pivoted upon a pin 110 projecting radially from the shaft 67 which is rotatable simultaneously with the bracket 65 while the other is secured to a pin 111 projecting radially in the opposite direction from the pin 110 and carried by a sleeve 112 which is free to rotate on the shaft 67. A bar 113 is fastened to said sleeve and runs rearwardly to the block 70 to which it is secured. The rear ends of the movable leaves 54 are fastened to plates 114 which rest upon brackets 115 rigidly bolted to the guide plates 28 not far from the front edges of the saws. The upper surface of these brackets is curved concentric with the axis of the shaft 67.
- 45 The plates 114 are provided with knuckles 116 to which are hinged by knuckles 117 the plates 117' to which are secured the U-shaped shoes 118, which inclose the front edges of the saws at the points where they exert their cutting action upon the stave blank. Curved brackets 115, constitute a support for plates 114, in their angular perpendicular movements and which are pivotally connected to plates 117'. Therefore when the chain guide is raised and lowered perpendicularly, by means of rollers 42, mounted in oscillating rocker arm 45, acting against cam 48, the curved brackets 115, attached to chain guide are lifted and lowered therewith, thereby causing the shoes 118, attached to plates 117'—plates 114, and table leaves 54, to ascend and descend angularly.

larly in unison therewith, and it necessarily follows that plates 114, supporting plates 117' to which shoes 118 are secured, necessarily slide out over curved brackets 115 when ascending and inwardly when descending. The inner legs of these shoes serve as a support for the edges of the stave between the saws, and control the curvature of the stave by determining the relative height of said edges with reference to the center of the stave which is supported by the chain guide. The outer legs of said shoes are only a convenient means of supporting the inner legs, and any equivalent means of support may be used. The hinging of the plate 117' to plate 114 is in order to permit the shoes to swivel with the saw brackets and thus follow the saws when the latter are converged or separated by the cam action of the rollers and strap upon the fingers 94. The plates 117' are each pivoted by bolts 119' to one end of a link 119 whose other end is pivoted by a pin 120 parallel with the saw mandrel to lugs 121 on the upper side of the corresponding tail piece 90. These links act in unison with the links 109 which support the leaves, and their purpose is to hold the shoes 118 parallel with the plane of the saws in their upward and downward travel and for the further purpose of holding and converging the leaves 54 in unison and in line with the saws. Leaves 54 have a triple purpose as they are mounted and held in a horizontal position and act as a table to support the stave blank, to hold the shoes 118 in a horizontal position, and by moving in or out in unison with the saws over the curved brackets 115 which are concentric with the axis of the shaft 67, the leaves act as a gage to determine the width of the stave a given blank will make.

It will also be observed that the upper portions of the chain guides 28 are cut away to permit the shoes to be moved in close to the chain when a very narrow stave is being jointed. This is shown in Fig. 4, where the guide plates 28 are shown as being extra deep at this point to give them sufficient rigidity. The table bar 27 is also made deep at this point, and is beveled to an edge below to permit the saws to approach closely.

Extending laterally from each of the plates 117' is an arm on which is supported a sheet metal plate 123 to receive the strips cut from the edges of the stave blank.

Immediately above each shoe is a presser roll 124 pivoted upon a stud 125 projecting from a slide 126 mounted upon a horizontal arm 127 and secured adjustably thereto by a set screw 128. The arm 127 is bent outwardly and then downwardly forming a lever which is secured to a pivot pin 129 parallel with the saw mandrel mounted in a bearing 130 forming part of the standard for the saw mandrel. The lower end of

this lever abuts against a helical spring 131 whose other end rests against a portion of the bracket 65 or 66 as the case may be. An adjusting screw 127' mounted in a lug 201 takes against the back of the lever 127 to limit the downward movement of the presser roll. These spring pressed rolls press the edges of the stave yieldingly down onto the shoes 118, and since the center of the stave is supported at a higher level by the rigid chain guide, the stave will be curved to correspond with the bilge of the barrel of which it is to form a part, so that the edges of said stave will be jointed properly to make a tight joint when the barrel is assembled.

In the rear of each saw and in the plane of revolution thereof is an upright blade 132 which is mounted on a lug 133 on the bracket carrying the saw and serves to keep the kerf open and as a guard.

It will be observed that the cutting edge of the saw meets the stave blank at a point in or near the vertical axis of the stud on which the saw bracket is swiveled. In order to maintain this relation of these parts, it is necessary to provide for saws of different diameters and also to take up wear as the diameter of any given saw lessens from frequent sharpening. To meet this requirement, the saw standard is provided with a carriage 134 which rests upon ways 135 which are inclined to the horizontal surface of the bracket 65 or 66 on which they are erected, preferably at an angle of about 45 degrees, in a plane normally parallel with the travel of the carrier chain. The carriage and the ways are preferably rabbeted together, and can be relatively adjusted by means of clamping bolts 136 passing through slots in the ways. Movement in one direction carries the saw upward and forward toward the cutting point, while movement in the opposite direction carries it downward and backward. The outer end of the standard is provided with a foot 137 in which is a slot 138 parallel with the surface of the ways 135, so that the standard can be properly secured by the screw 139 passing through said slot into the bracket.

The saws and the chain carrier are driven by belting (not shown) in the usual manner.

The operation of the machine is as follows:—Automatic stopping mechanism which has been omitted for the sake of clearness, halts the chain carrier 20 with a hook link 21 a short distance in front of the saws. The operator places a stave blank ~~upon~~ under the hook, and then throws the lever 84 to move the leaves 54 in or out until their ~~upper~~ bowed edges, serving as a gage, rest upon the outer edges of the blank and determine the width of the proposed stave. This operation also tilts the saws to the proper regular position. The machine is then started.

ed, and as the link 22 comes up over the curve of the idle sprocket 16 its shoulder engages the rear end of the blank. As the chain straightens out, this shouldered link turns up vertically behind the stave and exerts a thrust upon it, forcing its forward end snugly into the hook of the forward link 21 and clamping the blank solidly to the chain, besides holding it centrally between the saws, so that an evenly divided or corresponding bilge and joint is formed on its two edges. The stave blank rests on the upper edge of the chain and the movable leaves 54. The spring-actuated presser rolls 124 keep the blank pressed firmly down upon the inside edges of the shoes 118 which serve as supports for the edges of the stave and give it its proper elevation in time with its travel between the saws, so as to control the shape to be given to the edges of said stave. The eccentric 107 operating on the levers 103 104, as described, the links 101 102, the rock arms 100, 97, the rollers 96 and the fingers 94, has caused the brackets 65 66 to be turned on their pivot studs 72 73 so that when the stave blank reaches the saws 55, they are converged at their rear edges, as shown in Fig. 17. As the blank moves forward between the saws the crank pin 47 and connecting rod 46 rock the roller 42 so that it acts upon the cam 48 and gradually lifts the table, chain, movable leaves, shoes, and presser rolls, the links 36 38 holding the chain guide level and enabling the stave blank to be acted upon by those teeth of the saws which are farther and farther apart as the chain guide and shoes rise, thus giving the stave its proper increase in width. Meanwhile the eccentric sprocket 14 is giving sufficient slack to the chain to enable it to be raised in this manner and yet keep taut at all times, assuming the quarter to be jointed and the saws now acting on the bilge portion. As the stave proceeds the brackets are gradually turned by the cam fingers and rollers to bring the saws more and more toward parallelism, (Fig. 18) until at the middle of the stave they are exactly parallel, and the shoes and chain guide are at their highest level. From this point onward, the shoes and chain guard are gradually lowered, as before described, and the saws are gradually separated at the rear until the bilge is formed, then remaining stationary until the end of the stave is reached, at which time the saws stand as shown in Fig. 19, and the shoes and chain guard have been lowered to the original level. The axis of each saw mandrel 60 is at all times radial to the curvature of the edge of the stave.

The rollers 108 are set a given distance away from the surface of the eccentric 107 for the purpose of creating a dwell or non-action of the camming rollers 96 during the time that the quarter on the stave is being

operated upon by the saws. According to Fig. 1, the greater radius of the eccentric 107 is at a point above and to the right of the reference numeral 107, and by the time this greater radius in its movement upward has passed the right hand roller 108', the cam rollers 96 will be at their upward end of travel, from which time on there is a dwell until the increased radius of the cam or eccentric comes in contact with the left hand roller 108.

Now after the forming of the first quarter, on the stave, the increased radius of the eccentric comes in contact with the roller 108 at the left, causing the rollers 96 to gradually descend, thereby increasing the divergence of the saws at their back portions and enabling the saws to form the curve or bilge of the stave along the middle thereof. After the greater radius of the eccentric has passed the left hand roller 108, there is a dwell of the rollers 96, allowing the last quarter to be formed and the stave to be carried out from between the saws. The eccentric then engages the right hand roller 108' again and throws up the rollers 96, thus closing the saws again at the back ready for the next stave.

When the hooked link reaches the left hand idle sprocket 15 the curvature of the chain in passing over said sprocket opens said link and releases the finished stave. The machine is calculated to operate upon four staves during one revolution of the chain, the driving shaft making one revolution for each stave, and repeating the entire cycle of operations at each revolution; the time consumed being that required for each stave to pass between the saws.

In accordance with the provisions of the patent statutes I have described the principle of operation of my invention, together with the apparatus which I consider to be the best embodiment thereof; but I wish it to be understood that the invention can be carried out by other mechanism, not departing from the scope of my invention as a whole, and that the apparatus shown is only illustrative.

Having thus described my invention what I claim is:—

1. A machine for jointing a stave which comprises a pair of rotating saws whose planes of rotation are inclined in opposite directions, means for passing the stave blank horizontally between said saws, means for lifting and lowering said stave during such passage, and means for maintaining said saws with their planes of revolution tangent to the longitudinal curvature of the edges of said stave and their cutting edges at a fixed distance apart at the points where the cutting is being effected.

2. A machine for jointing a stave which comprises a pair of rotating saws whose

planes of rotation are inclined in opposite directions, means for passing the stave blank horizontally between said saws, means for lifting and lowering said stave during such passage, and means for swiveling said saws on vertical axes passing substantially through the points of cutting to keep their planes of revolution tangent to the longitudinal curvature of the edges of said stave at the points where the cutting is being effected.

3. A machine for jointing staves, comprising a pair of saws, means for swiveling them on axes passing through their cutting points, shoes adjacent to the cutting edges of said saws for supporting a stave blank close thereto, means for raising and lowering the stave blank as it passes between said saws, and means for raising and lowering said shoes on diverging lines to support the stave blank at its edges as it rises and falls.

4. A machine for jointing staves, comprising a pair of saws, supports therefor mounted to swivel on vertical axes passing through the cutting points of said saws, shoes adjacent to the edges of said saws and supporting the edges of a stave blank close thereto and between said saws, means for raising and lowering the stave blank as it passes between said saws, means for raising and lowering said shoes on diverging lines supporting the stave blank at its edges as it rises and falls, levers pivoted on the swiveled saw supports, spring-actuated presser rolls on said levers making contact with the upper side of said stave blank over said shoes, and following the angular and swiveling movements of the saws.

5. A machine for jointing staves comprising an endless carrier for the stave blanks, a rigid support for said carrier, means for raising and lowering said support and carrier while the latter is in motion, rotating saws located on each side of said carrier, means for tilting said saws toward and away from said carrier, measured in a plane transverse to the travel of the carrier, and means for swiveling said saws on vertical axes coinciding substantially with the points of cutting.

6. A machine for jointing staves comprising an endless chain carrier, a rigid support therefor, means for raising and lowering said support and that part of the carrier resting thereon, and a sprocket for driving said chain adapted to slack the same to permit said support to be raised, two circular saws on opposite sides of said carrier mounted to swivel on vertical axes at their points of cutting, and means for swiveling said saws in synchronism with the rise and fall of said carrier.

7. A machine for jointing staves comprising an endless chain carrier, a rigid support therefor, means for raising and lower-

ing said support and that part of the carrier resting thereon, and an eccentric sprocket for driving said chain, two circular saws on opposite sides of said carrier mounted to swivel on vertical axes at their points of cutting, and means for swiveling said saws in synchronism with the rise and fall of said carrier.

8. A machine for jointing staves comprising an endless chain carrier, a rigid support therefor, means for raising and lowering said support and that part of the carrier resting thereon, an eccentric driving sprocket for said chain, and idle sprockets at the ends of said support, one of said idle sprockets being adjustable longitudinally of said support, two circular saws on opposite sides of said carrier mounted to swivel on vertical axes at their points of cutting, and means for swiveling said saws in synchronism with the rise and fall of said carrier.

9. A machine for jointing staves comprising a pair of rotatable saws, a longitudinal shaft, members for supporting said saws each capable of independent angular movement about the axis of said shaft, pivots for said supporting members in line with the cutting edges of said saws, rods pivoted to said members, a vertical plunger in line with the pivots, on which said rods are swiveled, means for adjusting said plunger up and down to tilt the saws toward and away from each other and to hold their cutting edges at any given distance apart, and means for giving said saw-supporting members a swiveling movement independently of their tilting movement to vary the horizontal angle between the planes of said saws without varying the width between their cutting edges.

10. A machine for jointing staves, comprising a pair of rotatable saws, a longitudinal shaft, members for supporting said saws each capable of independent angular movement about the axis of said shaft, pivots for said supporting members in line with the cutting edges of said saws, rods pivoted to said members, a vertical plunger in line with said pivots, on which said members and supporting rods are swiveled, means for adjusting said plunger up and down to tilt the saws toward and away from each other and to hold their cutting edges at any given distance apart, and means for automatically giving said saw supporting members a variable reverse swiveling movement independent of their tilting movement and corresponding to the angularity assumed by the saw supporting members to vary the horizontal angle between the planes of said saws without varying the width between their cutting edges.

11. A machine for jointing staves comprising an endless chain carrier, a rigid

table for supporting the same, means cutting in a plane which is inclined to a plane at right angles to the travel of the work, parallel links connecting said table with the frame of the machine, a cam secured to said table, means for driving said chain, and a rocker arm engaging with said cam and operating synchronously with said driving mechanism.

10 12. A machine for jointing staves comprising an endless chain carrier, means cutting in a plane which is inclined to a plane at right angles to the travel of the work, a table comprising a flat plate and a narrow bar arranged in a vertical plane and in line with said flat plate, guide plates secured to said flat plate and bar, parallel links pivoted to said table and to the frame of the machine, a cam secured adjustably 15 to the under side of said table, a rocker arm engaging with said cam, and a driving shaft carrying a crank pin connected to said rocker arm.

13. A machine for jointing staves comprising a longitudinal cylindrical shaft, a short sleeve thereon having a slot, curved blocks fitting said shaft and sleeve above and below, a stud extending radially from said shaft through the slot in said sleeve 20 and through one of said blocks, a second stud extending radially from said sleeve through the other block, and cutter supporting members swiveled on said studs.

14. A machine for jointing staves comprising a longitudinal cylindrical shaft, a short sleeve thereon having a slot, curved blocks fitting said shaft and sleeve above and below, a stud 25 extending radially from said shaft through the slot in said sleeve and through one of said blocks, a second stud 72 extending radially from said sleeve through the other block, and cutter supporting members swiveled on said studs, said studs 72, 73 supporting said members in line with the cutting edges of the saws, rods pivoted to said members, and a vertically movable plunger in line with said pivots, on which said rods and cutter supporting members swivel.

50 15. A machine for jointing staves comprising a longitudinal cylindrical shaft, a short slotted sleeve thereon, curved blocks fitting said shaft and sleeve, studs projecting radially through said blocks, one being inserted in said shaft and the other in said sleeve, brackets swiveling on said studs and having rearwardly-extending tail pieces, rotary cutters mounted on said brackets, and means for separating and approaching said tail pieces to swivel said brackets on their studs, means of automatically causing said cutters to reverse their horizontal angles and to converge while the stave is passing out from between said cutters.

65 16. A machine for jointing staves com-

prising a longitudinal cylindrical shaft, a short slotted sleeve thereon, curved blocks fitting said shaft and sleeve, studs projecting radially through said blocks, one being inserted in said shaft and the other in said sleeve, brackets swiveling on said studs and having rearwardly-extending tail pieces, rotary cutters mounted on said brackets, and means for separating and approaching said tail pieces to swivel said brackets on their studs, said means consisting of cam fingers on said tail pieces, and actuating members engaging with said cam fingers and operatively connected with the driving shaft of the machine.

17. A machine for jointing staves comprising a longitudinal cylindrical shaft, a short slotted sleeve thereon, curved blocks fitting said shaft and sleeve, studs projecting radially through said blocks, one being inserted in said shaft and the other in said sleeve, brackets swiveling on said studs and having rearwardly-extending tail pieces, rotary cutters mounted on said brackets, and means for approaching said tail pieces to 70 swivel said brackets on their studs, said means consisting of cam fingers on said tail pieces, a bell crank lever engaging therewith, a cam on the driving shaft of the machine, and operative connections between said cam 75 and said bell crank lever.

18. A machine for jointing staves comprising a longitudinal cylindrical shaft, journaled in bearings, a short slotted sleeve thereon, curved blocks fitting said shaft and sleeve, studs projecting radially through said blocks, one being inserted in said shaft and the other in said sleeve, brackets swiveling on said studs and having rearwardly-extending tail pieces, rotary cutters mounted on said brackets, and means for approaching said tail pieces to 80 swivel said brackets on their studs, said means for swiveling said cutters being adapted to cause them to converge and diverge a varying amount and remain stationary while forming the quarters, said variable means being governed automatically when changing the angular separation of said cutters for varying widths 85 of staves.

19. A machine for jointing staves comprising a longitudinal cylindrical shaft, a short slotted sleeve thereon, curved blocks fitting said shaft and sleeve, studs projecting radially through said blocks, one being 90 inserted in said shaft and the other in said sleeve, brackets swiveling on said studs and having rearwardly-extending tail pieces, rotary cutters mounted on said brackets, and means for separating and approaching said 95 tail pieces to swivel said brackets on their studs, said means consisting of cam fingers on said tail pieces, a bell crank lever, studs thereon carrying rollers engaging with the inner faces of said fingers, a strap on said 100

- bell crank lever having portions engaging with the outer faces of said fingers, a cam on the driving shaft of the machine, pivoted levers carrying rollers engaging therewith, and links connecting said levers with said bell crank lever.
20. A machine for jointing staves comprising means for supporting the stave blank horizontally, rotary cutters, means for swiveling the same to conform to the longitudinal curvature of the stave, means for adjustably spacing the cutters, and means whereby such spacing automatically varies the operation of the swiveling means.
- 15 21. A machine for jointing staves comprising means for supporting the stave blank in a horizontal position, rotary cutters, means for varying the angular separation of said cutters to accommodate stave blanks of different widths, and means for swiveling said cutters to cause them to converge and diverge a varying amount and remain stationary while forming quarters, said means being governed automatically by the angular separation of said cutters.
- 20 22. A machine for jointing staves comprising an endless chain, a rigid table therefor, guide plates on said table, curved brackets projecting laterally from said guide plates, movable leaves adjacent to said guide plates and resting at one end on said brackets, tilting cutters, means for tilting them, and operative connections between said means and said movable leaves, whereby the latter will always be kept in line with said cutters.
- 25 23. A machine for jointing staves comprising an endless chain carrier, guide plates between which said chain travels, inclined saws, means for tilting the same, shoes embracing one edge of said saws, and means for causing said shoes to follow the movements of said saws, said guide plates being cut away adjacent to the cutting edges of said saws to permit said shoes to approach closely to the chain carrier.
- 28 24. A machine for jointing staves comprising an endless chain carrier, a rigid bar forming a table on which said chain is supported, guide plates secured to the sides of said bar, inclined saws on opposite sides of said bar, means for tilting said saws, shoes embracing one edge of said saws, and means for causing said shoes to follow the movements of said saws toward and away from said bar, the bar being deep and beveled downwardly at a point where the saws are located, and the guide plates being cut away at a point opposite the shoes to permit the shoes to approach the chain closely.
- 30 25. A machine for jointing staves comprising an endless chain, a rigid table therefor, guide plates thereon, inclined saws, means for tilting the same, shoes embracing the inner edge of said saws, movable leaves adjacent to said guide plates and attached to said shoes, and means for causing said leaves and shoes to follow the tilting movements of said saws.
- 35 26. A machine for jointing staves comprising an endless chain, a rigid table therefor, guide plates thereon, inclined saws, means for swiveling said saws on a vertical axis at or near the cutting point, means for giving a uniform degree of reverse swiveling movement to the saws, shoes embracing one edge of said saws, hinge joints for said shoes at or near the cutting point, and operative connections between said shoes and the means for swiveling said saws so that the movements of the saws will be followed by said shoes.
- 40 27. A machine for jointing staves comprising laterally adjustable and swiveled saws, an endless carrier, a rigid table therefor, guide plates thereon, means for lifting and lowering said carrier, table and guide plates as the stave blank passes between said saws, outwardly bowed leaves adjacent to said guide plates, and means for moving said leaves laterally to keep them in line with the cutting edges of the saws.
- 45 28. A machine for jointing staves comprising laterally adjustable and swiveled saws and means for giving said saws a variable and uniform degree of reverse swiveling movement, an endless chain, a rigid table therefor, guide plates thereon, movable leaves adjacent to said guide plates, shoes hinged to one end of said leaves, thereby holding shoes in parallel position, a longitudinal shaft, brackets angularly movable about the axis of said shaft, links connecting said brackets with said shoes, and connections at the other end of said shaft whereby the other ends of said leaves are angularly movable about the axis of said shaft.
- 50 29. A machine for jointing staves comprising a longitudinal shaft, two brackets angularly movable about the axis thereof, longitudinally-inclined ways on each bracket, a carriage adjustable on the ways of each bracket, and a saw mandrel journaled in bearings in said carriage.
- 55 30. A machine for jointing staves comprising two saws inclined toward each other, brackets carrying said saws and swiveled on axes coinciding substantially with the cutting points of said saws, ways on said brackets inclined to the planes in which they swivel, and carriages adjustable on said ways and having bearings for the saw mandrels, thereby affording means for adjusting elevation and position of said saws so as to maintain the cutting point substantially in line with said axes.
- 60 31. A machine for jointing staves comprising a longitudinal cylindrical shaft, a short slotted sleeve thereon, curved blocks fitting said shaft and sleeve, pivots 72, 73

projecting radially through said blocks, one being inserted in said shaft and the other in said sleeve, members for supporting saws each capable of independent angular movement about the axis of said shaft, said pivots 72, 73, supporting said members in line with the cutting edges of said saws, supporting rods pivoted to said members, a vertical plunger in line with said pivots, on which 10 said members and supporting rods are swiveled, means for adjusting said plunger up and down to tilt the saws toward and away from each other and to hold their cutting edges at a variable distance apart, and 15 means for automatically giving said saws and supporting members a variable reverse swiveling movement corresponding to the angularity assumed by said saws and supporting members and to vary the horizontal 20 angles between the planes of said saws without varying the width between their cutting edges.

32. A machine for jointing staves comprising means for supporting the stave blank horizontally, rotary cutters, means for variably swiveling the same to conform to the longitudinal curvature of varying widths of staves, shoes adjacent to the cutting edges of said cutters for supporting a stave blank close thereto, means for raising and lowering a stave blank as it passes said saws, and means for raising and lowering said shoes on diverging lines to support and to control the design or curvature given to stave at its edges during the rise and fall of said stave 35

In testimony whereof I have signed my name to this specification in the presence of two subscribing witnesses.
